UNITED STATES PATENT OFFICE.

RANSOM E. OLDS, OF DETROIT, MICHIGAN, ASSIGNOR TO OLDS MOTOR WORKS, OF DETROIT, MICHIGAN, A CORPORATION OF MICHIGAN.

CARBURETER FOR EXPLOSION-ENGINES.

SPECIFICATION forming part of Letters Patent No. 761,392, dated May 31, 1904.

Application filed June 17, 1902. Serial No. 112,047. (No model.)

To all whom it may concern:

Be it known that I, RANSOM E. OLDS, a citizen of the United States, residing at Detroit, in the county of Wayne and State of Michigan, 5 have invented certain new and useful Improvements in Carbureters for Explosion-Engines, of which the following is a specification, reference being had therein to the accompanying drawings.

10 The invention relates to improvements in carbureters for explosion-engines, and more especially designed for use in connection with automobiles.

It is the object of the invention to provide 15 means under the control of the operator for varying the explosive charge and for maintaining the proper proportion of oil and air; and it is a further object to obtain a simple construction and one which will not easily get out 20 of order.

The invention therefore consists in the construction as hereinafter described and claimed.

In the drawings, Figure 1 is a vertical longitudinal section through the carbureter. 25 Fig. 2 is a horizontal section on line $\alpha\alpha$ looking from the bottom.

A is a hollow casing adapted to be connected to the induction-pipe of the engine or directly to the engine-cylinder.

30 B is a casing adapted to be connected to the casing A by registering flanges C and D, bolted or otherwise secured to each other. These two casings together form an air-induction conduit. The section A at the point of juncture with the casing B has its area restricted by the internal flange E.

F is a slide-valve arranged in adjacence to the flange E and having a port G therein adapted in one position of the valve to register with the restricted port H, formed by the flange E. At one end of the port G is a slot I, which when in registration with the port H will still further restrict the same.

J is an oil-inlet conduit entering the casing 45 B and partially formed integral therewith. This conduit passes centrally beneath the port H and has formed, at its upper end a seat K for the valve L. The latter is in the form of

a rod having a tapering point for engaging with the seat K and passing upward centrally 50 through the port H and out through an aperture in the upper wall of the casing A. The rod L is also provided with a flange M, surrounding the same and arranged just above the plane of the valve F.

N is an adjustable stop, preferably in the form of a screw, engaging with a lug O upon the casing A and extending in alinement with the rod L in close proximity to the upper end thereof.

P is a rod slidingly secured in bearings in the casing A and extending parallel to the valve F. One end of this rod is bent downward and engages with an aperture in the projecting end of the valve F, forming a 65 means of operating the latter.

Q is a spring sleeved upon the rod P, one end abutting against a stop or collar R thereon and the other against the casing A.

S is an operating-rod connected with the 70 rod P and extending to a suitable point where it is under the control of the operator.

The parts being constructed as shown and described, in normal position the tension of the spring Q bearing against the collar R will 75 hold the rod P and valve F in a position where the slot I in the latter is in registration with the port H, thereby greatly restricting the area of said port. The rod L will also normally rest upon the seat K, and the weight 80 of this rod is preferably sufficient to counter-balance the hydrostatic pressure of oil in the conduit J, which is supplied from suitable source, such as the tank T, arranged at a higher level.

When in the operation of the engine an air-suction is produced by the movement of the piston, an air-current will be drawn through the conduit formed by the casings A and B, which current will be compelled to pass 90 through the restricted passage formed by the slot I in the valve F. In thus passing through the slot I the current will be directed against the flange M on the valve-rod L, with the effect that said rod will be lifted from its seat, 95 allowing the oil to escape through the conduit

J and to be absorbed by the passing air-current. The degree of opening of the valve may be regulated to any desired point by an adjustment of the stop N, which limits the upward movement of the rod L.

Whenever it is desired to increase the explosive charge, the operator by bearing upon the rod S will slide the rod P against the tension of the spring Q and will move the valve F so as to register its larger opening G partially or wholly with the port H. This will permit a larger volume of air to pass through the casings, and at the same time a proportionately larger quantity of oil will be introduced in the current, being drawn therein by the increased air-blast. It will be seen from Fig. 1 of the drawings that the valve-seat K is arranged a slight distance below the plane of the valve F and in the center of the enlarged chamber in the casing B. This construction is of great importance, as the oil is thus introduced into the air-current below the point of greatest restriction and where the suction produced by said current is not as great as in immediate proximity to the valve. The result will be that the amount of oil drawn from the conduit J when the valve is raised from its seat and when the valve F is in its normal restricted position will not be greater than needed for carbureting the quantity of air which passes through the restricted port I. When, however, the area of the opening of the valve is increased, the distance between the oil-valve seat and the open-air port is less in proportion to the area of the latter, the effect being the same as the movement of the oil-conduit nearer to the restricted port. The result is that the quantity of oil introduced into the air-current is quite accurately proportioned to the volume of the latter, while the change in the oil-supply is entirely automatic.

It is to be noted that no adjustments are required excepting that of limiting the throw of the valve-stem L, and this when once set need not be altered. It will be also seen that no adjustable valve is required for controlling the oil-supply. The construction is thus well adapted to be used in automobiles, as the average operator is not a mechanic and will obtain better results where the adjustment of the oil-supply is beyond his control. For obtaining the initial charge for the engine the stem of the valve L may be lifted, so as to permit a small quantity of oil to flow from the conduit J into the air-conduit. In order that this will be distributed and absorbed by the air-current, a conical foraminous diaphragm U is preferably arranged within the casing B, extending from the valve-seat K to the wall of the casing. The oil admitted from the conduit J will thus flow upon this diaphragm and will be absorbed by the air-current passing therethrough.

While I have described a specific construction of parts, it is evident that modifications

might be made without departing from the spirit of my invention, the essential features of which are set forth in the claims.

What I claim as my invention is—

1. A carbureter comprising a conduit 70 through which an air-current is passed having a restricted passage therein, an oil-conduit opening into said air-conduit adjacent to but not directly in said restricted passage and a valve for further restricting said restricted 75 passage adapted to vary the area thereof and thereby to produce a variable suction of oil into said air-conduit proportional to the quantity of air passing therethrough.

2. A carbureter comprising a conduit 80 through which an air-current is passed having a restricted passage therein, an oil-conduit opening into said air-conduit adjacent to but not directly in said restricted passage, a valve for closing said oil-conduit adapted to be 85 opened by the air-current in said air-conduit, and a valve for further restricting said restricted passage adapted to vary the area thereof and to thereby produce a variable suction of oil into said conduit proportional 90 to the quantity of air passing therethrough.

3. A carbureter comprising a conduit through which an air-current is passed having a restricted passage therein, an oil-conduit opening into said air-conduit centrally in line 95 with but not directly in said restricted passage and a gate-valve for extending across said restricted passage adapted to further restrict the same variably whereby a variable quantity of oil will be drawn into said air-conduit proportional to the quantity of air passing therethrough.

4. A carbureter comprising a casing forming a conduit for the passage of air having a restricted passage therein, an oil-conduit 105 opening into said air-conduit adjacent to but not directly in said restricted passage, a valve for closing said oil-conduit having the stem thereof passing through said restricted passage, a flange on said stem for lifting the 110 same by the pressure of the air-current and a gate-valve for variably further restricting said restricted passage and having a slot through which said oil-valve stem passes in the closed position of said gate-valve adapted 115 to permit the passage of a small quantity of air therethrough.

5. A carbureter comprising a casing forming a conduit for the passage of air having an angular bend therein and a restricted passage 120 adjacent to said bend, an oil-conduit opening into said air-conduit centrally in line with but not directly in said restricted passage, a valve for closing said oil-passage having its stem passing through said restricted passage 125 and outward through an aperture in the casing, a stop for limiting the movement of said stem, a flange on said stem for operating the valve by the pressure of the air-current, and a gate-valve for further variably restricting 130

said restricted passage and slotted for the passage of said stem therethrough.

6. A carbureter comprising a casing forming an air-conduit having a restricted passage 5 therein, an oil-conduit opening into said air-conduit adjacent to but not directly in said restricted passage, a valve for closing said oil-conduit adapted to be operated by the movement of the current a gate-valve for variably 10 further restricting said restricted passage and means for operating said oil-valve from without said casing to form the vapor for the initial charge.

7. A carbureter comprising the casings A 15 and B together forming an air-conduit, the internal flange E on the casing A forming a restricted passage H, an oil-inlet pipe in the

casing B opening centrally in line with the passage H and below the plane of the flange F, a valve L for closing said oil-conduit having its stem passing through the passage H and outward through an aperture in the casing, an adjustable stop in line with the end of said stem, the flange M upon said stem in the passage A, the gate-valve F having the aperture G therein and the slot I for the purpose described.

In testimony whereof I affix my signature in presence of two witnesses.

RANSOM E. OLDS.
